Primary Examiner — Mark A Goodwin*Assistant Examiner* — William B Melliar(74) *Attorney, Agent, or Firm* — Che-Yang Chen; Law Office of Michael Chen(57) **CLAIM**

The ornamental design for solar deck light, substantially as shown and described.

DESCRIPTION

FIG. 1 is a top, front and right side perspective view of solar deck light, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings depict portions of the solar deck light that form no part of the claimed design.
